UNITED STATES PATENT OFFICE

ERNST KÖHN, OF BERLIN-WILMERSDORF, GERMANY, ASSIGNOR TO THE FIRM ZAHN & CO., G. M. B. H., OF BERLIN, GERMANY

CALCINING FURNACE AND METHOD OF OPERATING THE SAME

Application filed August 3, 1927, Serial No. 210,350, and in Germany December 30, 1926.

My invention relates to improvements in calcining furnaces and the method of operating the same.

In the circular calcining furnaces with stationary hearths, hitherto known, the parts which are most sensitive to attack by heat and chemicals, namely the central pedestal with the arm cross and securing devices for the arms, are located within the heated furnace. These parts therefore had to be made of expensive acid and fireproof steel and exchanging of the stirrer arms during operation was practically impossible, despite proposals for convenient exchanging; for after a short period of operation the exchangeable members were attacked and changed, so that the exchange could only be effected when the furnace was allowed to get cold, when the securing devices could be conveniently reached.

According to the present invention the centre of the calcining furnace, wherein the devices for securing and moving the stirrer arms are located, is surrounded by masonry and thereby separated from the heated calcining space. Within the separated part therefore are located the centre shaft with the arm cross, and the devices for securing the stirrer arms to the arm cross. The stirrer arms move in a slot in the masonry surrounding the centre, which slot is packed in such a manner that, for example acid vapours cannot reach the shaft on the centre pedestal. The latter can therefore be of simple machinery cast iron.

The secure operation of the furnace according to the invention is further guaranteed by the feature that at the point at which the feeding arrangement is provided, heating from below does not take place, thus ensuring that the hearth plates are not so rapidly attacked by the freshly introduced and at first most strongly reacting chemicals.

Further the heating in the neighbourhood of the feed point is not so strong in that the gases proceeding directly from the fire and therefore are there hottest reach the material being calcined only at the end of its path through the annular furnace shortly before it is removed. The particular form taken

by the annular furnace according to the invention therefore permits the counter current principle to be employed, which has hitherto only been proposed in long extended sulphate furnaces, but which has not yet been used in circular furnaces.

The furnace according to the present invention is particularly adapted for the manufacture of sulphate from salt and sulphuric acid or salt and bisulphate, but can also be used for other calcining processes.

The accompanying drawing shows by way of example an embodiment of furnace in accordance with the present invention. Figure 1 shows the furnace in vertical section and Figures 2 and 3 show sections on the lines 2-2 and 3-3 of Figure 1.

The annular muffle furnace is indicated by 1 and the unheated circular inner space by 2. The fire gases which come from the heating place 19 pass first in the direction of the arrow into the upper heating channel 3, then pass through the passage 4 into the lower fire channel 5 traversing the latter in the same direction and after having thus passed twice round the annular muffle furnace leave through the passage 6. The feeding of the furnace takes place through an opening 7, the removal of the calcined materials through the outlet opening 8. As appears from Fig. 3, the brickwork below the opening 7 is solid, the fire channel 5 ending at opposite sides of the said opening and away therefrom.

The inner circumferential wall of the furnace surrounding the chamber 2 is formed with a continuous circumferential slot 15, and in order to support the top part of the brickwork an annular plate 20 is provided which is suspended by means of bars 21 from beams 22 disposed above the furnace. To prevent the escape of gases from the calcining chamber suitable packing means are provided. As shown the said packing means are in the form of upper and lower rings 16 made from channel irons and fixed to the inner wall of the brickwork, the said rings being engaged by rings 17 fixed to the arm-cross and formed at their top with a circumferential channel 23 engaged by the downwardly directed flange of the upper channel iron. The lower

ring 16 and the ring 23 are filled with sand or other packing medium. In order to prevent bending of the arm-cross due to the weight of the stirrer arms, it is provided 5 with downwardly directed arms 18 carrying rollers 24 supported on an annular track 25.

I claim:

1. A circular muffle calcining furnace, comprising an annular hearth having an inner circumferential wall formed with a continuous circumferential slot, heating means for said hearth, stirrer arms projecting through said annular slot from the median part of the furnace into the hearth, a ring carried by 10 said stirrer arms in position for covering said slot, packing members fixed to said circumferential wall and cooperating with said ring for closing said slot, and means for rotating said stirrer arms.

2. A circular muffle calcining furnace, comprising a stationary hearth having bottom and top walls, annular heating channels located above and below said hearth, the inner circumferential wall of said hearth being 25 formed with a circumferential slot, stirrer arms projecting from the median part of the furnace through said slot and into said hearth, means for rotating said stirrer arms, means for successively passing heating gas 30 through said heating chambers, and a feeding passage extending downwardly into said hearth, the portion of the bottom wall of the hearth below said feeding passage being made solid, and the connection between the 35 upper fire passage and the lower fire passage being made by a passage which when looking in the direction of the flow of the heating gas is located behind said feeding passage.

3. A method of operating circular muffle calcining furnaces provided with rotary stirrer arms, in which the fire gases first traverse 40 three quarters of the furnace through the upper fire passage, until they reach the freshly introduced materials and then again pass 45 round the furnace through the lower fire passage before they leave the furnace, while the stirring device moves the material to be calcined in a direction counter to that of the fire gases.

4. A circular muffle calcining furnace, comprising an annular hearth having an inner circumferential wall formed with a continuous circumferential slot smaller in height than the hearth, heating means for said 55 hearth, stirrer arms projecting through said annular slot from the median part of the furnace into the hearth, the said median part circumscribed by said circumferential wall having a diameter sufficient to permit access 60 to said stirrer arms, and means for rotating said stirrer arms.

5. A circular muffle calcining furnace, comprising an annular hearth having an inner circumferential wall formed with a continuous 65 circumferential slot, heating means for

said hearth, stirrer arms projecting through said annular slot from the median part of the furnace into the hearth, means for rotating said stirrer arms, and means movable with said stirrer arms for closing said slot.

70

6. A circular muffle calcining furnace, comprising a stationary annular hearth having bottom and top walls, annular heating channels located above and below said hearth, stirrer arms projecting into said hearth, means for passing heating gas through said heating channels, and a charging passage extending downwardly into said hearth, the heating channel below said hearth ending at opposite sides of said charging passage and 80 away therefrom thus providing a solid bottom between its ends below said charging passage.

In testimony whereof I hereunto affix my signature.

ERNST KLÖHN.
